UNITED STATES PATENT OFFICE.

BENJAMIN F. HAUGH, OF ANDERSON, INDIANA.

METHOD OF CASTING CAR-COUPING KNUCKLES.

1,078,499.

Specification of Letters Patent.

Patented Nov. 11, 1913.

Application filed August 11, 1910, Serial No. 576,711. Renewed September 9, 1913. Serial No. 788,935.

To all whom it may concern:

Be it known that I, BENJAMIN F. HAUGH, a citizen of the United States, residing at Anderson, in the county of Madison and 5 State of Indiana, have invented certain new and useful Improvements in Methods of Casting Car-Coupling Knuckles, of which the following is a specification.

The object of my said invention is to provide a knuckle for car couplings the pivot bearing in which will be true and smooth, as cast, without fitting or dressing, and also capable of resisting wear to a greater degree than the metal of which the body of 15 the knuckle is made, whereby the life of said knuckle may be prolonged and the expense of fitting the same reduced, and it consists not only in the improved form of knuckle, but also in the method of casting the same, 20 whereby the above objects are accomplished, all as will be hereinafter more fully described and claimed.

Referring to the accompanying drawings which are made a part hereof and on which 25 similar reference characters indicate similar parts, Figure 1 is a sectional view through a core box used for forming cores for the pivot holes, or bearing, to be used in the molds for casting the knuckles, Fig. 2 a 30 transverse section through the same on the dotted line 2—2 in Fig. 1, Fig. 3 a plan view of one of the knuckles in finished form, Fig. 4 a perspective view showing the pivot bearing lining separately, and Fig. 5 a sectional 35 view through the knuckle on the dotted line 5—5 in Fig. 3.

In said drawings the portions marked A represent the core box, B the core, and C the knuckle.

40 The core box A is made in two parts and of the usual, or any approved form, except that it is enlarged throughout its central portion from a shoulder a (see Fig. 1) near one end to another shoulder a' near the other 45 end. Between said shoulders the diameter of the core box is increased to receive a metal tube, or lining, c and said shoulders are of a depth to just correspond to the thickness of said lining so that its inner surface will be flush with the main face of the 50 core box. I have shown said lining c in Fig. 4 as a solid tube, but, as will be readily understood, it may be a plate rolled into a cylindrical form, or may be made up by several 55 curved sections, (as indicated by dotted

lines in Fig. 4), if preferred. Said lining of whatever form, whether a single part or several sections, is preferably made of self-hardening metal such as described in Re-issue Letters Patent No. 11,704, issued No. 60 November 29, 1898 to myself and G. H. Vincentt.

In forming the core the core box is opened and the lining c put in its place between the shoulders a and a'. The core 65 box is then closed and a core mold thus formed which is of uniform diameter from point x to point y and metal incased for the greater portion of its length. The core is made in the usual way by filling the core 70 box with sand, or other core material, properly prepared for the purpose. The core box is then opened, the core removed, including the lining c, which now incases the core for the greater portion of its length, 75 and said core is then placed in the mold, prepared in the usual way, for casting the knuckles. The ends of the lining c preferably do not extend quite to the ends of the 80 molds so that in the casting said lining is entirely incased by the metal of the knuckles, as shown most clearly in Fig. 5, the softer metal of the knuckle thus protecting the ends of the hardened metal of which 85 said lining is composed.

The knuckles are cast in the usual manner by pouring the molten metal into the mold to fill the same and surround the core, and allowing the same to cool, during which 90 cooling process the metal of which the lining c is composed hardens as described in the patent above mentioned. After the cooling is completed the knuckle is taken out of the mold and the core removed, leaving 95 a pivot bearing in the knuckle which is true, smooth and hard, requiring no dressing in order to fit it for use, as is customary with knuckles cast in the usual way. The labor and expense of fitting is thus not only saved but a knuckle is provided 100 which has been found capable of outwearing three knuckles made by the common method. A bearing is also secured which is adapted to give better results in use because of its true circular form, which enables the knuckle to turn freely and truly without binding or wabbling, as they do when the pivot bearings are imperfect, as is frequently the case 105 with knuckles of the ordinary construction.

Having thus fully described my said in- 110

vention, what I claim as new and desire to secure by Letters Patent, is:

1. The method of casting knuckles for car couplings which consists in first forming a core for the pivot bearing by placing a tubular lining in the core box, then forming said core principally within said lining, but extending outside each end thereof, then placing said core carrying said lining within

10 the knuckle mold, then pouring the molten metal into said mold around said core, then allowing the casting to cool, and then removing said core, substantially as set forth.

2. The method of casting knuckles for car couplings which consists in embedding a metal lining for the pivot bearing within the core box used for forming the pivot bearing core, forming said core within said lining in said core box, and with ends projecting 15 beyond the ends of said lining, removing said core incased by said lining from said core box and placing the same in the knuckle mold, pouring the molten metal into said knuckle mold around the core, allowing the 20 same to cool, then removing said knuckle, and then removing the core from the pivot bearing in said knuckle, substantially as set forth.

3. The method of casting car coupling knuckles consisting in taking a metal lining 25 having the characteristics that permit it to self-harden while cooling and closing the ends thereof, placing the closed-end tube in a knuckle mold, then pouring the metal 30 that is to form the knuckle in the mold

around the closed tube, gradually cooling the poured metal to slowly cool the closed tube within the knuckle and enable it to self-harden while in the knuckle metal, and finally removing the closure from the ends of 40 the hardened tube, whereby a straight smooth passage will be formed by the self-harden tube without machine work or drilling and the same be ready to receive the pivot pin of the knuckle.

4. The method of casting car coupling knuckles consisting in taking a metal lining and placing a core filling therein with the ends of the core projecting beyond the ends of the tube but leaving the outer and end 45 surfaces of the tube exposed, placing the closed tube in a mold, pouring molten metal in the mold around the exposed outer and end surfaces of the closed tube so as to retain the tube in place, allowing the casting 50 to cool, and finally opening the tube by removing the filling from the straight smooth inner surface, whereby the knuckle will be provided with a straight smooth passage ready to receive the pivot pin upon the cooling of the metal.

In witness whereof, I have hereunto set my hand and seal at Anderson, Indiana, this 6th day of August, A. D., nineteen hundred and ten.

BENJAMIN F. HAUGH. [L. S.]
